C. M. RICE

TRANSPARENT SIGN AND THE METHOD OF MAKING SAME

Filed April 5, 1926

UNITED STATES PATENT OFFICE.

CYRIL M. RICE, OF MONTREAL, QUEBEC, CANADA.

TRANSPARENT SIGN AND THE METHOD OF MAKING SAME.

Application filed April 5, 1926. Serial No. 99,924.

This invention relates to new and useful improvements in signs and the method of making same, and the object of the invention is to provide a sign of a transparent nature which will be inexpensive to manufacture and efficient in operation.

Another object is to provide a flexible sign of the class stated which will lend itself efficiently to all classes of advertising frames and manners of mounting same.

A further object is to provide a sign of the class stated which will be of robust construction and in which the advertising matter will be protected from the effects of the weather.

In my invention I provide a sign made from two pieces of flexible transparent material. The advertising matter is painted, printed or otherwise placed on the face of one sheet and covered by the other, the contacting surfaces being so treated that both sheets will unite when pressed together to form a single sheet of transparent material with the advertising matter positioned between the outside surfaces of the said single sheet.

In the drawings which illustrate my invention in one of the many forms it may be constructed—

Figure 1 is a side elevation of a typical sign which may be made according to my invention.

Figure 2 is a sectional plan view of the device shown in Figure 1 and taken on the line 2—2 thereof.

Figure 3 is a perspective view of the background element of the sign.

Figure 4 is a perspective view of the cover for the background.

Figures 5 and 6 show the positions of the cover and the background during the process of manufacture of the sign.

Figure 7 is an end elevation of the finished product.

Referring more particularly to the drawings, 11 designates a sheet of transparent material preferably celluloid and upon the upper face 14 of said sheet hereinafter called the background, is painted, printed or otherwise marked the advertising matter, which for illustrative purposes only I have

shown as Doe and Co. A cover 12 of similar material is shown in Figure 4 and this cover is preferably made of substantially the same shape as the background. The 55 face 13 of the cover and the face 14 of the background are then treated with a chemical such as benzol or acetone, which will cause the adjacent surfaces of the sheets to adhere to one another and knit together to 60 form a single sheet of flexible material of uniform thickness. The cover and the background are then placed in the position shown in Figures 5 and 6, that is with the treated surfaces adjacent one another and 65 with the painted or printed surface of the background uppermost, so that when the cover and the background are brought together as shown in Figure 7, and subjected to a predetermined pressure they will unite 70 and form a single sheet of transparent material with the advertising matter positioned within the material and between the surfaces 16 and 17. The material may then be bent by any process to suit the requirements of 75 the purchaser and as an illustration of same, I have shown in Figure 1, and in Figure 2, the material bent in the form of a cylinder 18 with ornamental ends or caps 19 placed at each end. Illuminating means such as 80 an ordinary electric lamp may be placed within the cylinder as indicated by dotted lines in Figure 1. This lamp may be connected in any suitable manner to a source of electrical supply by means of the plug 20. 85 Modifications may be made in the general construction of the device without departing from the spirit of the invention.

A sign constructed in the manner herein described is very efficient in service and provides a flexible sign of a transparent nature which is inexpensively manufactured and in which the advertising matter is protected from the effects of the weather by being positioned within the body of the sign. The 90 cover and the background may be made of any thickness and of any shape as desired.

Having thus described my invention, what I claim is:—

An advertising sign comprising an inner 100 cylindrical sheet of transparent celluloid having advertising matter applied directly

on the outer surface of said sheet, an outer cylindrical sheet of transparent celluloid enclosing said inner cylindrical sheet, said sheets having their contacting surfaces chemically treated and united by adhesion to form in effect a unitary cylinder wall with the advertising matter positioned be-

tween the inner and outer surfaces of said wall, caps closing the ends of said cylindrical sheets and illuminating means contained within the cylinder. 10

In witness whereof I have hereunto set my hand.

CYRIL M. RICE.
